H. SONNER

SASH LOCK

Filed July 18, 1923

UNITED STATES PATENT OFFICE.

HARRY SONNER, OF NEW YORK, N. Y.

SASH LOCK.

Application filed July 18, 1923. Serial No. 652,439.

To all whom it may concern:

Be it known that I, HARRY SONNER, a citizen of the United States, and a resident of the city of New York, borough of Queens, in the county of Queens and State of New York, have invented a new and Improved Sash Lock, of which the following is a full, clear, and exact description.

This invention has relation to locks and 10 has particular reference to an improvement in sash locks.

The principal object of the present invention resides in the provision of means for locking the upper and lower sashes of a 15 window against relative movement in a direction to open the same or to effect a further opening thereof if the same are partially open.

As a further object the invention contemplates a sash locking device of the character 20 set forth which is extremely simple in its construction, inexpensive to manufacture and install and which is highly efficient and thoroughly reliable in its purpose.

With the above recited and other objects 25 in view, the invention resides in the novel construction set forth in the following specification, particularly pointed out in the appended claim and illustrated in the accompanying drawings, it being understood 30 that the right is reserved to embodiments other than those actually illustrated herein to the full extent indicated by the general meaning of the terms in which the 35 claim is expressed.

In the drawings—

Figure 1 is a fragmentary vertical sectional view through a window equipped 40 with a sash lock constructed in accordance with the invention and illustrating the same in locked position.

Fig. 2 is a similar enlarged fragmentary view illustrating respectively in full and dotted lines the locked and unlocked positions of the latch member.

Fig. 3 is a fragmentary front view of the same.

Referring to the drawings by characters of reference A designates the conventional 50 form of window including upper and lower sashes B and C. The sash lock constituting the invention includes a rack bar 10 having a plurality of rack teeth 11 which is preferably secured in a vertical position on the 55 inner face of one of the side rails D of the upper sash. The pawl or latch 12 which con-

sists of a flat blade is mounted for pivotal movement in a substantially U-shaped base 13. In the preferred embodiment, as illustrated, the pawl is formed with integral laterally projecting trunnions 14 which are mounted in circular bearing openings 15 in the side walls 16 of the U-shaped base, the said bearing openings having communicating slots 17 which extend through their forward end edges to facilitate the assembly of the pawl or latch with the base. The bight or connecting web 18 of the base is apertured to receive therethrough fastening screws 19 anchored in the upper face of the upper or 60 meeting rail E of the lower sash. In order to provide means for normally swinging the pawl or latch 12 outwardly to a position for engaging the teeth 11 of the rack bar, a rearwardly projecting arm 20 is provided 65 on the pawl or latch 12 to the eye 21 at the free end of which a flexible element 22 is connected and by the free end of which element a weight 23 is carried. The flexible element or core 22 is trained through a guide 70 75 80 85 90 95 100 110 web 18 attached to the upper portion of the window frame. In order to provide means for holding the pawl or latch in a retracted position out of engagement with the teeth of the rack bar and against casual movement and at the same time to limit the forward swinging movement of the same beyond a predetermined angle, a spring 25 is employed, the rear end of which passes through an aperture 26 and the bight or connecting 90 95 100 110 web 18 is hooked over the rear end thereof. The major portion of the spring 25 projects upwardly and forwardly or outwardly at an angle to the bight or web 18 and passes through an aperture 27 in the pawl or latch with its outer end turned downwardly as at 28 to engage with and limit the outward swinging movement of the pawl whereby to prevent swinging of the pawl or latch to a position which would allow for displacement of the trunnions from the bearing openings 15.

In use and operation of the sash lock, the pawl or latch 12 when swung to a position for engagement with the rack teeth 11 as illustrated in Fig. 1, positively locks the sashes together against relative movement by a person from the outside to a position to open the window or increase the opening of the window after the same has been partially opened by a person from the inside, although the construction admits of the rela-

tive movement of the sashes with respect to each other for closing the window opening. In this instance the pawl will ratchet over the rack teeth 11 as will be clearly understood. The device will be found especially useful to lock the sashes of a window in partially open condition for the purpose of obtaining ventilation without allowing the gaining of access from the exterior or against the possible further opening of the window by children. The device will also function to lock the sashes in completely closed condition when desired. The spring 25 will serve to retain the latch or pawl 12 in its retracted position against casual displacement but in order to insure against accidental movement of the same into engagement with the rack teeth the flexible element or cord 22 may be engaged in the notch 17 as will be obvious.

I claim:

A device for automatically locking the upper and lower sashes of a window against relative opening movement from the outside, comprising a rack bar secured to the upper sash, and means mounted on top of the meeting rail of the lower sash for selectively engaging the teeth of the rack bar,

said means comprising a substantially U-shaped base having its bight portion attached to the top of the meeting rail and having circular bearing openings in the side walls thereof and reduced slotted portions extending from the circular bearing openings through the outer ends of the side walls, a substantially flat latch member having outwardly projecting trunnions of a width to snugly operate the bearing openings and of a thickness to admit of the introduction of the same through the slotted portions, an angularly disposed spring mounted between the side walls of the base having a down-turned outer terminal, said latch having an opening receiving said spring and engageable by the terminal to limit the outward swinging movement of the latch and to prevent turning of the same to a position to admit of separation of the latch from the base, said spring serving to frictionally hold the latch in its engaged relation to the teeth of the rack bar, and a weighted element connected with the latch for normally swinging the same to a position for engagement with the rack teeth.

HARRY SONNER.
